UNITED STATES PATENT OFFICE.

EDWARD CLEARY, OF BRIDGEPORT, CONNECTICUT, ASSIGNOR TO THE CONNECTICUT WEB COMPANY, OF BRIDGEPORT, CONNECTICUT, A CORPORATION OF CONNECTICUT.

HOSE-SUPPORTER BUTTON.

No. 851,980.

Specification of Letters Patent.

Patented April 30, 1907.

Application filed April 12, 1906. Serial No. 311,293.

To all whom it may concern:

Be it known that I, EDWARD CLEARY, a citizen of the United States, and a resident of Bridgeport, in the county of Fairfield and State of Connecticut, have invented certain new and useful Improvements in Hose-Supporter Buttons, of which the following is a specification.

My invention relates to certain new and useful improvements in buttons for garment or hose supporters, and the object of the invention is to provide an improved form of button for such supporters, which may be produced from two parts in an inexpensive and practical manner; to produce a button which in appearance will resemble a more expensive construction and which will be equally as durable and likewise as desirable in many respects; to provide a button the back portion of which may be formed of metal with means for its attachment to a web, and a head portion of softer material, which will not injure the garment, and is likewise adapted to be finished in various colors and in imitation of rubber, celluloid or fabric as desired.

Upon the accompanying drawings forming a part of this specification similar numerals of reference denote like or corresponding parts throughout the several figures and of which,

Figure 1, shows a perspective view of my improved button attached to a web and combined with a loop member, with which it is adapted to be used. Fig. 2, is a detached plan view of the button. Fig. 3, is a side elevation of the same, and Fig. 4, a transverse vertical cross section taken on line 4—4 of Fig. 2.

The button as before stated is formed of but two parts, with improved means for connecting one with the other, so designed as to permit of its production and assembling in the cheapest possible manner consistent with a first class and practical button.

Referring in detail to the characters of reference marked upon the drawing, 5 represents a webbing of the usual or any preferred kind, 6 a loop pivotally connected thereto having the usual enlarged upper portion 7 and a narrow throat or pocket 8 adapted to receive the head of a button when connected as in the engagement of a hose.

9 represents the base of the button, which as shown is formed of sheet metal, having 55 transverse slots 10—10 through which the before mentioned webbing 5 is threaded and attached in the customary way. The intermediate portion of this base member 8 is struck up to form a central annular hollow 60 shank 11 that is preferably narrower through its top than its base and which forms a socket for the top member.

12 indicates the top member of the button which is preferably formed of wood or like 65 soft material and comprises an enlarged oval head portion 13 and a reduced round stem portion 14 adapted to snugly fit in the socket of the annular shank portion, with its lower end finished even with the under side of the 70 base plate.

The parts are retained together in this position by means of one or more punched indentations 15 formed in the side of the circular shank portion in a way to force the metal of 75 said shank portion into the stem of the wood member, or said parts may be held together, by cramping the upper edge 16 of the shank against the stem thus further reducing the upper diameter of the shank portion in a way 80 to firmly grasp the stem. By forming the shank of the button larger through its base than its top the loop will slip up toward the head and more snugly hold the fabric against the under side thereof. The top or wood 85 member of the button is enameled to form a finish which can be produced in imitation of rubber, leather, fabric or other materials, and likewise produces a slightly yieldable engagement for the material, besides forming a 90 more desirable frictional engagement for said material than is obtainable by the use of a nickel plated or other finished metal head.

The base member of the button can be inexpensively produced by a single operation, 95 and the wood member which is obviously first turned up, can likewise be assembled and attached by a single additional operation which materially decreases the cost of producing a button of this kind.

In the use of my button, when applied as shown in the accompanying drawing, the same is placed under the edge of the garment to which it is to be attached, the loop member drawn down over the head of the fabric 105 covered button, and then the throat of the

loop drawn up under the head in a way to firmly engage and clamp the fabric over the button and intermediate of it and the loop.

Having thus described my invention what 5 I claim and desire to secure by Letters Patent is:—

In a hose supporter button, the combination with a wooden head having a reduced stem, of a sheet metal base plate having an annular shank portion struck up therefrom to receive the stem of the head and having its

upper annular edge forced into the said stem, and additional indentations in the side of the shank to engage the stem of head.

Signed at Bridgeport, in the county of 15 Fairfield, and State of Connecticut this 6th day of April, A. D., 1906.

EDWARD CLEARY.
